COMBINATION LAMP, CLOCK AND DUAL
PLANT HOLDER

Ben Rubin, Chicago, Ill.

Application August 13, 1952, Serial No. 21,032

Term of patent 3½ years

(Cl. D48—20)

To all whom it may concern:

Be it known that I, Ben Rubin, a citizen of the United States, residing at Chicago, in the county of Cook, and State of Illinois, have invented a new, original, and ornamental Design for a Combination Lamp, Clock and Dual Plant Holder, of which the following is a specification, reference being had to the accompanying drawing, forming part hereof:

Figure 1 is a front elevational view of a combination lamp, clock and dual plant holder showing my new design;

Figure 2 is an end elevational view thereof;

Figure 3 is a rear elevational view; and

Figure 4 is a top plan view.

Both ends of the combination lamp, clock and dual plant holder have the exact same appearance.

I claim:

The ornamental design for a combination lamp, clock and dual plant holder, as shown and described.

BEN RUBIN.
